GUARDIAN TRUST & SAVINGS BANK, OF TOLEDO, OHIO, TRUSTEE

METHOD FOR BENDING TUBES OF FIBER AND SIMILAR MATERIAL

Application filed February 17, 1930. Serial No. 429,188.

The invention relates to a method for bending tubes constructed of hygroscopic material such as vulcanized fiber, hard paper tubes, or tubes composed of other cellulose or fibrous material.

In the manufacture of fibrous tubes it has been the custom to produce the same by winding upon a mandrel a wet web of fibrous pulp such as cellulose pulp, the wet web of pulp being formed by a cylinder mold or other web-forming mechanism and being conveyed to the winding mandrel by any suitable form of conveying means. As a result of this operation, there is formed upon the mandrel a tube having a wall which is substantially homogeneous. When the winding operation is completed, the tube itself is moist and it is then ordinarily subjected to a drying operation by which the moisture is removed.

The present invention relates to an improved method of bending such fibrous tubes after the forming mandrel has been removed. This may be accomplished before the wet pulp of which the tube is composed is permitted to dry, or if it is dried the tube may be moistened so as to condition it for the bending operation, for it is a prerequisite that the tube shall be in a condition to bend, and in a moist condition they bend best. A moist paper or fiber tube is easily collapsible since the walls thereof under these conditions possess little strength or resistance.

One of the problems which presents itself in the bending of such tubes is to prevent the malformation of the tube and to maintain the circularity of the tube in cross section. I have solved this problem by causing a yielding outward pressure to be exerted uniformly against the interior of a moist tube during the bending operation, by means of gas pressure within the tube, and then removing the moisture from the tube while it is still subjected to such pressure. The gas under pressure is preferably maintained within the tube during and after the bending operation, and this is preferably accomplished by sealing the tube gas tight and applying heat to the tube.

According to the preferred embodiment of

my process, therefore, the following steps will be employed: First, the tube, if in set or hardened form, is soaked in water until it becomes moist and flexible. This flexibility may of course be obtained by employing a tube which has just been formed from the web or pulp and which has not been permitted to dry. The essential feature, in any event, is to obtain the desired flexibility of the fibrous material of which the tube is composed. When this flexibility has been obtained, the tube is inserted in a bending matrix and closed gas tight. Heat is then applied to expand the air within the tube and also to generate steam from the moisture contained within the tube walls. Sufficient heat is applied to produce a pressure which will prevent collapsing of the walls of the tube during the bending operation. Preferably the heat should be uniformly applied to the outside of the tube, both above and below, and in this manner substantially uniform temperatures inside and out of the tube are maintained. The preferable mode of supplying heat is by means of gas burners which may be very accurately regulated to produce the desired degree of pressure within the tube.

According to the preferred embodiment of the invention a number of tubes may be bent at one time and in a single matrix, and in such case it is desirable that the gas burners be provided with branches above and below the tubes, and corresponding in number with the number of tubes. A single control device may be employed for regulating the supply of gas to all the branches.

When the gas pressure has thus been obtained within the tube or tubes, the bending operation is performed while carefully maintaining the pressure within the tubes. In this way a uniform bend is obtained and no marring or collapsing of the tube results. After bending, the tubes are maintained in the forms or matrices and kept gas tight until the hardening of the tubes is completed. This setting or hardening operation is preferably accomplished by a continued supply of heat, which performs the dual operation of drying the tubes and maintaining the internal gas

pressure during such drying and heating operation.

The advantage of gas pressure for maintaining the circularity of the tubes over other means which have been employed for similar purposes is self-evident, namely the uniformity of pressure throughout the tube, thus avoiding marring or ridging at any portion and providing a smooth interior or exterior surface. Moreover, a perfect control of the pressure may be had where gas is used as the expanding medium by regulation of the heat supplied, the same heat serving both for drying and for maintaining pressure within the tube.

While the gas pressure alone is sufficient to perform the desired operation, nevertheless it is sometimes desirable to fill the tube with fine granular material such as moist sand, sawdust and the like. It is not essential that the sand be moist, although this is preferable. Such granular material assists in maintaining the circularity of the tube, particularly prior to the time that the gas pressure is sufficient to prevent collapsing. Where moist granular material is used, such moisture produces steam on heating of the tube, which steam produces pressure to assist in maintaining the circularity. If desired, where already fixed tubes are to be bent, such fiber tubes may be first filled with sand or granular material to insure the maintaining of circularity, and then while so filled may be soaked in water to obtain the desired flexibility. Obviously when so filled there is no danger of the tubes collapsing before being placed in the bending matrices.

The bending operation may be desirably performed in an apparatus set forth in the accompanying drawing, in which:

Figure 1 is a top plan view of the bending apparatus especially designed for bending gas filled tubes and for heating the gas during the bending and subsequent drying of the tubes in order to maintain the proper degree of pressure within the tubes;

Figure 2 is a longitudinal sectional view of the apparatus, the section being taken through one of the tubes, certain parts being shown in elevation, this view showing the relation of parts when the tubes are in place within the forms, and just before the bending operation;

Figure 3 is a view similar to Fig. 2 showing the parts of the device when the tubes are being bent;

Figure 4 is a detail vertical sectional view showing a means for heating the tubes, and

Fig. 5 is a detail of one of the extension plates attached to the lower forms.

As shown, the bending device consists of a bed member 10, and an upper press member 11 pivotally connected to the bed member by means of the hinge 12. The bed member 10 carries the lower halves 13 of a plurality of tube forms, herein shown as three in number,

while the upper member 11 carries the upper halves 14 of the tube forms. These forms are of the proper degree of curvature desired in the completed bent fiber tube.

For bending fiber tubes which have already set, it is necessary to first soak them in water until they become moist and flexible. The tubes 15 are then inserted in the bending matrices as shown in Fig. 2, the lower ends of the tubes are closed air tight by means of gaskets 16 which are held in place by caps 17, which in turn abut against projections 18 on the lower portion of the form. The caps 17 serve to protect the ends of the tube against injury or marring during the bending operation. To each of the lower forms is pivoted an extension shield 19, the purpose of which is to prevent marring of the tube at that end of the tube form, as would obviously be the case if no such means were provided. In order to maintain each of the tubes gas tight, spring pressed closure members 20, of rubber or like material, are provided at the ends of the tubes opposite the gaskets 16. These closure members are carried by threaded rods 21 extending through a bar 22, which is carried by a lever 23 secured to one of the pivoted shields 19. Springs 24 react between the bar 22 and the closure-members 20.

In order to prevent collapsing of the moist fiber tubes, heat is applied, which expands the air within the closed tubes and generates steam from the moisture carried by the tubes. To supply the necessary heat, gas burners 25 and 26 above and below the tube forms are provided. Sufficient pressure will be generated within the tubes by this heating operation to prevent collapsing of the tubes as the upper form members are lowered to the position shown in Fig. 3, by means of an operating handle 27 or other operating means, and the form may be secured in this lowered position by means of a latch member 28, provided with a notch 29, which coacts with a pin 30 upon the operating handle 27. As the tubes are bent the extension shields 19 are rotated about their pivots 31 and prevent marring of the tubes at the ends of the lower tube forms 13. As the shields are rotated, the rod 23 carried by the central space, swings upwardly, carrying with it the bar 22 and the closure members 20, which swing in the same arc as the tubes themselves, and in this manner the gas tight fit is maintained at all times.

After the fiber tubes have been bent they are maintained in the bending forms until they have completely dried, and hardened in the bent form. The drying operation will be assisted by the application of heat from the burners 25 and 26. The gas pressure is maintained within the tubes until they have hardened sufficiently to prevent collapsing.

It will be noted that accurate control of the temperature and pressure within the tubes may be had at all times by regulating the

flame from the gas burners, a valve 32 being provided for this purpose. It is to be further noted that uniform heating at the top and bottom of the tubes is obtained by means of the upper and lower series of burners 25 and 26. Both upper and lower burners are branched and their number corresponds to the number of the tubes to be bent, so that the temperatures and pressures will be equalized for all of the tubes undergoing the bending operation. The upper set of burners 26 is connected to the source of supply by flexible members 33, whereby the burners 26 are readily moved upwardly and downwardly with the upper hinged member 14 of the matrix. This arrangement is intimately connected with the improved process in that it permits heat to be applied to the top of the tube to supply the necessary pressure within the tube before the bending operation takes place, as clearly indicated in Fig. 2. When the upper member 14 is lowered to the position shown in Fig. 3, the burner members 26 are likewise carried downwardly so as to remain in close proximity to the bent tube and maintain the desired gas pressure uniformly within the tubes during the heating operation.

Having thus described the invention, what is claimed as new and desired to be secured by Letters Patent is:

1. A method of forming a fixed bent fiber tube which comprises sufficiently moistening the tube to render it flexible, closing the tube gas tight, heating the closed tube sufficiently to generate gas pressure within the tube sufficient to maintain the circularity of the tube during bending, bending said tube while maintaining said gas pressure, and drying the gas tight closed bent tube to cause it to set by continued application of heat, thereby continuing the internal gas pressure during the setting of the tube.
2. A method of bending and drying a moist fiber tube composed of cellulose pulp, which comprises closing the flexible tube gas tight, heating the closed tube sufficiently to generate gas pressure within the tube sufficient to maintain the circularity of the tube during bending, bending said tube while maintaining said gas pressure, and drying the gas tight closed bent tube to cause it to set by continued application of heat, thereby continuing the internal gas pressure during the setting of the tube.
3. A method such as herein described, which comprises bending a straight moist tube into the desired curvature while causing yielding outward fluid pressure to be exerted uniformly against the internal surface of such tube by heating and thus expanding the fluid therein, and then removing the moisture from said tube while it is subjected to such pressure.
4. A method of bending a moist fiber tube which comprises subjecting the tube to bend-

ing stress and simultaneously confining the outside of the tube to prevent radially outward movement in any direction and obstructing the inside against radially inward movement in any direction by confining a fluid within the tube.

In testimony whereof I affix my signature.
